UNITED STATES PATENT OFFICE.

OSCAR CARLSON, OF DANNEBROG, NEBRASKA, ASSIGNOR OF ONE-HALF TO W. A. LINGFORD, OF DANNEBROG, NEBRASKA.

TRAIN-OPERATED GATE.

Application filed May 4, 1926. Serial No. 106,673.

The invention relates to train operating travel of the train until the train reaches gates, and has for its object to provide a device of this character comprising a vertically movable pivoted gate adjacent a railroad crossing and train operated mechanisms located at opposite sides of the gate, up and down the track and constructed whereby upon approach of a train from either direction the gate will be moved to a substantially horizontal position by the actuation of one of the mechanisms and returned to inoperative raised position by the actuation of the other mechanism, according to the direction of travel of the train.

15 A further object is to provide the gate actuating mechanism at opposite sides of the gate with downwardly extending pivoted arms, the lower ends of which are provided with yieldable rod connections and with bell crank levers which control the downward movement of the gate and rock shafts having upwardly extending arms, with which a member carried by a train engages, and which rock shafts are provided with downwardly extending members having rollers, which rollers, upon a rocking of the rock shaft in one direction force the downwardly extending arms in opposite directions thereby imparting pulls on the bell crank levers according to the direction of movement of the train for holding the downwardly extending arms in operative position until released by the train after passing the crossing.

35 A further object is to provide a pivoted releasing lever adjacent the rollers which cooperate with the downwardly extending arms, link connections between the releasing levers and the rollers, the links being connected to the releasing levers below their pivotal points and forming means whereby through rod connections, between the lower ends of the releasing lever, the train operated arms will be moved to normal vertical position by the operation of the actuating arm carried by one of the mechanisms to one side of the gate after the train has passed the crossing and according to the direction of movement of the train.

40 50 55 A further object is to provide the releasing levers with upwardly and oppositely extending arms which overlie the rollers within the casings, and which arms prevent rocking or operation of the mechanism at the opposite side of the gate in the direction of

the same and rocks the rock lever therein. Also to provide the rock levers with weighted cranks which assist in returning the train engaging arms to normal vertical position and insures a positive operation of the mechanism, which mechanisms are similarly constructed but are in reverse relation to each other.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:—

Figure 1 is a side elevation of the device, showing the same applied to a conventional form of railroad track.

Figure 2 is a vertical longitudinal sectional view through the gate actuating mechanism.

Figure 3 is a top plan view of one of the gate actuating mechanisms.

Figure 4 is a vertical longitudinal sectional view through the gate casing.

Figure 5 is a detail sectional view taken on line 5—5 of Figure 4.

Referring to the drawings, the numeral 1 designates a conventional form of railroad track, 2 the gate casing disposed to one side of the track and preferably at a road crossing and 3 a pivoted gate which is pivotally connected at 4 to the upper end of the casing 2. The gate 3 is mounted on a rock shaft 5 by means of a bracket 6, and the shaft 5 is provided at opposite sides of the gate 3 with upwardly extending arms 6, which arms have pivotally connected thereto at 7 downwardly extending links 8. Connected at 9 to the downwardly extending links 8 are coiled springs 10, the lower ends of which are connected to adjusting bolts 11, which bolts are in turn connected to the arms 12 of bell crank levers 13, which bell crank levers are pivotally mounted at 14 within the casing 2. Bell crank levers 13 are provided with downwardly extending arms 15, to the lower ends of which are connected at 16 rods 17, which rods extend in opposite directions as clearly shown in Figure 2, and through the pipes 18 which are connected

to the mechanism casings 19. The mechanism casings 19 are disposed at opposite sides of the casing 2, and a substantial distance therefrom, and are disposed adjacent the 5 track 1 in a position where the shoe 20 carried by a cow-catcher 21 of a train will engage the rollers 22 of the operating arms 23 as the train passes in either direction. As the train approaches the first mechanism 10 reached by the train is actuated, thereby moving the gate 3 to a horizontal position, and after the train passes the gate and reaches the second mechanism, the second mechanism is actuated, the first mechanism 15 released, the gate allowed to return to normal inoperative position and the second mechanism is then returned to normal position by means of the first actuated mechanism, all of which will be hereinafter fully 20 set forth. Gate 3 returns to normal position as shown in Figure 4 by means of gravity, and through the influence of the weight 24 carried by the rear end thereof, and which weight is adjustably mounted on the gate 25 by means of bolts 25 which extend through the gate and through an elongated slot 26 in the weight, therefore it will be seen the gate may be accurately balanced in relation to the springs 10 whereby its action will 30 be positive, and at the same time balanced whereby the springs, when stretched by the actuation of the bell crank levers 13, will easily move the gate to a horizontal position, and into engagement with the shoulder 27 35 which will limit the downward movement of the gate. It will be noted that the spring 10, which is not actuated will contract thereby preventing movement of the bell crank lever which is not actuated, consequently 40 mechanism connected to the bell crank levers will be maintained in relative position at all times.

Casings 19 are disposed at opposite sides of the gate casing 2 adjacent the track 1 and 45 the mechanism therein is in reverse relation as shown in Figure 2, therefore in describing the mechanism the same numerals will apply to the mechanism in both cases. The lower ends of the arms 23 terminate in horizontally disposed rock shafts 27 which are 50 rockably mounted in bearing members 28 carried by the undersides of the casing covers 29. One of the ends of the rock shafts 27 terminates in downwardly extending arms 30 which arms are provided with rollers 31. Rollers 31 engage the downwardly extending 55 pivoted levers 32 below the arcuate surfaces 33 thereof, and in positions whereby upon the inward rocking of either of the levers 23, rollers 31 will be forced arcuately against the levers 32, thereby moving said levers in the direction of the arrow *a* according to 60 the direction of travel of the train. By providing the arcuate surfaces 33, it will be 65 seen that the rollers 31 will hold the levers 32 in operated positions. Assuming the train is moving in the direction of the arrows *b*, Figures 1 and 2, and the lever 32 has been moved in the direction of the arrow *a*, the lower end of the lever 32 70 will be held in operated position and the spring 34, which is interposed between the lever and the nut 35 will be compressed slightly, however a pull is imparted on the adjacent rods 17, which rods will rock the 75 adjacent bell crank lever 13 thereby forcing the gate 3 to a horizontal position through the connecting member 11, spring 10, link 8 and arm 6, and said gate will be held in lowered horizontal position by the engagement 80 of the roller 31 with the arcuate surface 33. Upon the movement of either of the levers 23, a release lever 36, which is pivotally connected at 37 to a bracket 38 is rocked through the medium of the link 39, which is pivotally connected at 40 to the release lever 36 below the pivotal point 37, and which link 39 is provided with an elongated slot 41, in which is slidably mounted a pin 42 carried by the roller 31, therefore 90 it will be seen that the upper curved end 43 of the release lever will be moved upwardly and outwardly out of engagement with the roller 31, and at the same time the coiled spring 44 which surrounds the release 95 rod 45 and is interposed between the lower end of the release lever and with nuts 46 is compressed, thereby positively holding the release lever 36 in the other casing 19 and the mechanism against movement until actuated by the train. The same reference numerals applied to the release mechanism above set forth apply to the release mechanism in the other casing 19. As the train 100 passes the first mechanism the operating arm 23 thereof is left in position shown in Figure 1, and the gate 3 is held in a horizontal position by said mechanism. As the train passes the gate 3 traveling in the direction of the arrow *b*, the shoe 20 thereof engages the roller 22 of the arm 23 of the other mechanism, rocking the same in the direction of the arrow *c*, and which operation moves the roller 31 in the direction of the arrow *b* against the upper curved portion 110 43 of the release lever 36, thereby causing its lower end to move in the direction of the arrow *e*, which will impart a pull on the rod 45, which in turn will impart a pull on the lower end of the other release lever 36, 115 thereby causing the link 39, carried thereby to pull the roller 31 out of engagement with the arcuate surface 33, and allow the downwardly extending arm 32 to return to normal 120 position which will release the mechanism which controls the pivoted gate 3 and allows said gate to move to raised inoperative position under the influence of the weight 24 carried thereby. The rock shafts 27 are provided with cranks 47 on which weights 48 125 130

are disposed, and which weights assist in returning the mechanisms to normal position after an operation thereof, especially during the releasing operation. The rod 45 is preferably provided with a turn buckle 49 for adjustment purposes, and which turn buckle is disposed in the casing 2. The above operation takes place when the train travels in either direction, therefore it will 10 be seen no matter which way the train is traveling the arm 3 will be moved to horizontal position by the engagement of the member 20 with the arm 23 of the nearest casing 19, and the member 20 after passing 15 the crossing will engage the other arm 23 and restore the mechanisms of both casings 19 to normal positions as well as allowing the gate to swing upwardly to inoperative position.

20 From the above it will be seen that a train controlled gate is provided which is simple in construction the working parts thereof entirely encased and protected from the weather and the mechanism constructed in 25 a manner whereby it is positive in its operation, the parts reduced to a minimum, and the device may be easily and quickly applied to a railway crossing.

The invention having been set forth what 30 is claimed as new and useful is:—

1. The combination with a pivoted railroad crossing gate, of train actuated control means for said gate, said control means comprising casings at opposite sides of the gate, rock shafts in said casing, upwardly extending arms carried by said rock shafts in the path of an abutment carried by a train, downwardly extending pivoted arms within the casing, downwardly extending arms carried by the rock shafts, arcuate cam surfaces carried by the downwardly extending arms and with which the rollers cooperate, operating connections between the downwardly extending arms and the pivoted gate 40 whereby upon an outward movement of the pivoted arms said gate will be moved and held in closed position, and releasing mechanisms disposed in said casings and cooperating with each other whereby said downwardly extending arms will be released.

2. A train actuated pivoted gate mechanism, said mechanism comprising a pivoted

gate, casings disposed at opposite sides of said gate, rock shafts in said casings, upwardly extending operating arms carried by 55 said rock shafts, downwardly extending arms carried by said rock shafts, rollers carried by said downwardly extending arms, downwardly extending pivoted levers within the casings in reverse relation to each other, arcuate surfaces carried by said pivoted levers and with which the rollers cooperate, connections between the downwardly extending arms and the pivoted gate, said arcuate surfaces cooperating with the rollers 60 for holding the upwardly extending arms and the pivoted levers in operated position, pivoted release levers within the casings in reverse relation to each other, upwardly and outwardly curved arms carried by the release levers and overlying the rollers, link connections between the rollers and the release levers and connected to the release levers below their pivotal points and a connection between the release levers. 70

3. A gate actuating mechanism train controlled, said mechanism comprising spaced casings, horizontally disposed rock levers in said casings, upwardly extending arms carried by said rock shafts, downwardly extending arms carried by said rock shafts, downwardly extending pivoted levers within the casings in reverse relation to each other, rollers carried by said downwardly extending arms, said rollers cooperating with the inner sides of the downwardly extending levers whereby they are forced outwardly to operative position and held in operative position, operating connections between the downwardly extending levers 80 and the pivoted gate, downwardly extending release levers pivotally mounted within the casing, a member connecting said release levers together, arms carried by the release levers in reverse relation to each other, and overlying the rollers, link connections between the rollers and the release levers in reverse relation to each other, said link connections being pivotally connected to the pivoted release levers below their pivotal 90 points. 100

In testimony whereof I hereunto affix my signature.

OSCAR CARLSON.
